CARRIER FOR PNEUMATIC DISPATCH SYSTEMS

Wesley F. Grover, Detroit, Mich.

Application April 19, 1946, Serial No. 663,399

4 Claims. (Cl. 243—32)

1

This invention relates to a carrier for a pneumatic dispatch system and more particularly to a carrier for charge sales items.

In large department stores, for example, it is customary for the sales girl to place the charge slip in a pneumatic carrier which is then dispatched through a pipe line to a sorting desk. At the sorting desk the girl will open up each carrier, ascertain the initial of the surname of the person making the charge, reinsert the slip in the carrier, close the same and dispatch the carrier to the charge desk handling charge accounts of persons having that particular initial. In a busy department store such mode of handling is relatively slow and laborious.

It is an object of this invention to produce a carrier, and particularly a carrier for charge slips, which facilitates, simplifies and expedites the handling of such carriers at the sorting desk. This object is accomplished by providing the carrier with a window through which the chargee's name can be readily read and with holding means within the carrier for holding the charge slip in position both while the carrier is being closed and transported through the carrier system.

Fig. 1 is an elevation showing the carrier loaded ready to be dispatched through the pneumatic tube.

Fig. 2 is an elevation of the carrier with the door open and in position to receive the charge slip.

Figs. 3 and 4 are sections along the lines 3—3 and 4—4 of Figs. 1 and 2, respectively.

My carrier comprises an outer cylindrical shell 1 having an opening 2 therein and an inner cylindrical shell 3 having an opening 4 therein. The inner shell is rotatably mounted within outer shell in a conventional manner so that relative rotation of inner shell 3 within outer shell 1 closes opening 2, Fig. 1, or opens the same when openings 2 and 4 coincide, Fig. 2. The carrier is provided at each end with felt buffers 5 and 6 fixed respectively to outer shell 1 and inner shell 3. Thus, by grasping buffers 5 and 6 and rotating one while holding the other, inner shell 3 can be rotated to open opening 2 to permit insertion of the charge slip or whatever else is being transported in the carrier.

Shells 1 and 3 are preferably made of metal or other opaque material.

Shell 3 is provided with a window opening 11 which is closed with a transparent closure or window 7 preferably of transparent plastic material. Closure 7 fits within inner shell 3 and is held in place by means of fingers 8 which are

2

struck out of shell 3 and overlap the longitudinal edges of closure 7, as shown. Since window 7 is made of resilient thermoplastic material and curved to the cylindrical contour of shell 3, it is not necessary, but is preferable, for fingers 8 to overlap closure 7. The overlapping portion of fingers 8 preferably have a slight clearance as at 9 with the inside face of window 7 for purposes described below.

10 Since the charge slip 10 is folded and inserted in the carrier through opening 2 in outer shell 1 and opening 4 in inner shell 3 when the carrier is open, that is, when openings 2 and 4 coincide, it is necessary to rotate the shells relative to each other to close the carrier, Figs. 1 and 3. This relative rotation of the inner and outer shells will displace the charge slip and, further, the charge slip must also remain in place while traveling through the carrier system. Therefore, I have 15 placed a stop 12 in the form of a semi-circular metal strip which has its ends secured to the inside of shell 3 as at 13 and 14. While the carrier is open the credit slip, or whatever other type of readable material is being transported, is inserted 20 into the carrier with one edge 15 of the credit slip in contact or held in the corner formed by the stop 12 and the inside face of the shell 2 adjacent window 7. The other end of the charge slip can be engaged in clearance 9 between lip 8 25 and the transparent window 7, Figs. 3 and 4. If one edge of the slip is not interengaged with lugs 8, stop 12 will hold the slip in place and prevent the same from turning while the carrier is being closed. Charge slip 10, of course, is positioned in 30 the carrier with the customer's name, as shown in Fig. 1, against the transparent window 7 so that it can be readily read without any need for opening the carrier.

When the charge slip 10 is positioned within 35 inner shell 3 it is curved and naturally tends to straighten out. However, the slip is longer than opening 4 in shell 3 and therefore the ends of the slip project under the ends 16 of shell 3 which maintains the charge slip curved and under tension. Stop 12 also cooperates with the windowed portion 7 of shell 3 to maintain slip 10 in position. Hence, in actual practice the interengagement of one edge of the slip in clearance 9 under lip 8 is not at all necessary and 40 for the most part the carrier will be used without engaging the slip under lip 8.

I claim:

1. A carrier for a pneumatic dispatch system comprising inner and outer relatively rotatable shells each having an opening through the wall

thereof adapted to coincide in one position of the shells whereby an article having a legend thereon may be passed through said openings and inserted within said inner shell, a second opening through the wall of said inner shell spaced circumferentially from said other opening in said inner shell, said second opening coinciding with the opening in the outer shell and forming a window exposing the interior of said inner shell when the carrier shells are rotated to closed position, and a transparent closure for said second opening whereby when said carrier is closed the legend on said article therein can be read through said transparency.

2. A carrier for a pneumatic dispatch system comprising inner and outer relatively rotatable shells each having an opening through the wall thereof, said openings coinciding when the carrier is open to permit access to the interior of said carrier and said openings being offset when the carrier is closed, a second opening through the wall of said inner shell communicating with and exposing the interior of said inner shell, and a transparent closure on said inner shell for said second opening, said second opening being spaced circumferentially from the first opening in said inner shell and adapted to coincide with the opening in the outer shell when the carrier is closed, said second opening in said inner shell forming a window of substantial size in said inner shell whereby an article having a legend thereon can be placed within the inner shell with the legend toward said transparent closure where it can be read when the carrier is closed.

3. A carrier for a pneumatic dispatch system comprising inner and outer relatively rotatable shells each having an opening therein, said openings coinciding when the carrier is open to permit access to the interior of said carrier and said openings being offset when the carrier is closed, a second opening in said inner shell, and a transparent closure therefor, said second opening be-

ing spaced circumferentially from the first opening in said inner shell and adapted to coincide with the opening in the outer shell when the carrier is closed, a stop positioned in said inner shell between the two openings whereby an article having a legend thereon can be placed within the carrier against said stop and with the legend toward said transparent closure while the carrier is open and where it can be read when the carrier is closed, said stop serving to hold the article in said position while the shells are rotated relatively to each other to close said carrier.

4. A carrier for a pneumatic dispatch system comprising inner and outer relatively rotatable shells each having an opening therein, said openings coinciding when the carrier is open to permit access to the interior of said carrier and said openings being offset when the carrier is closed, a second opening in said inner shell, a transparent closure on said inner shell, said second opening being spaced circumferentially from the first opening in said inner shell and adapted to coincide with the opening in the outer shell when the carrier is closed whereby an article having a legend thereon can be placed within the carrier with the legend toward said transparent closure where it can be read when the carrier is closed, and means within the inner shell for holding said article within the inner shell with the legend toward said window whereby the article will be thus held in position during the closing and transporting of said carrier.
